NILS J. A. WAHLBERG, OF PITTSBURGH, PENNSYLVANIA, ASSIGNOR TO WESTINGHOUSE ELECTRIC & MANUFACTURING COMPANY, A CORPORATION OF PENNSYLVANIA.

INSULATOR TROLLEY-CONDUCTOR CLAMP.

1,387,524.

Specification of Letters Patent. Patented Aug. 16, 1921.

Application filed September 13, 1919. Serial No. 323,555.

To all whom it may concern:

Be it known that I, NILS J. A. WAHLBERG, a citizen of the United States, and a resident of Pittsburgh, in the county of Allegheny and State of Pennsylvania, have invented a new and useful Improvement in Insulator Trolley-Conductor Clamps, of which the following is a specification.

My invention relates to trolley-conductor supporting and insulating devices and particularly to trolley-conductor clamps used in conjunction with suspension insulators.

One object of my invention is to provide a device of the above indicated character that may be cheaply and expeditiously manufactured, be simple and durable in construction and be easy to install.

Another object of my invention is to provide a suspension insulator and a trolley-conductor hanger that shall be permanently connected together during the molding or forming operation of the insulating material.

Heretofore, it has been usual to provide suspension insulators and trolley-conductor hangers as separate devices. This has required considerable machine work on the devices themselves as well as the provision of machined extra parts and subsequent operations of assembling and installing the several separate parts.

In practising my invention, I provide a suspension insulator and a trolley-conductor clamp that are permanently connected together during the forming of the insulating material, thus providing a single structure having no superfluous or loose parts between the insulator and the clamps, whereby installation thereof is facilitated.

The single figure of the accompanying drawing is a side view, partially in elevation and partially in section, of a device embodying my invention.

My device comprises, in general, a suspension insulator 1, of a type usually employed in supporting trolley conductors, and a trolley-conductor clamp or gripping device 2 for engagement with a trolley conductor 3.

The specific structure of the clamp 2, aside from a portion thereof co-operating with the insulator 1, constitutes no part of

my invention, and will not be described in greater detail than is necessary to a clear understanding thereof.

The clamp 2 comprises an inverted body member or hood 4 of substantially trough shape for the reception, between its sides 5, of conductor-engaging ears 6 that are moved outwardly at their upper edges and inwardly at their lower edges by a longitudinal wedge 7. The wedge 7 extends through openings in the ends of the member 4 and, when driven therethrough to the position shown in the drawing, moves the ears 6, as above described, to gripping engagement with the conductor 3.

A projection 8, formed integral with, and disposed at the top of, the member 4, has a head 9 that is located within the insulator 1. The insulator 1 comprises an outer metal sheath or casing 10, having a threaded boss 11 for attachment to a suitable supporting structure (not shown), and a body 12 of insulating material, preferably a composition, molded therein.

During the construction of the device, the outer end of the projection 8, having the head 9, is inserted in the casing 10, and the insulating material 12 is poured or pressed, while in a plastic state, into the casing and around the projection and head.

After the insulating material 12 becomes hardened, the insulator 1 and the clamp 2 are permanently secured together.

The arrangement provides a unitary structure having substantially all of the mechanical advantages of the usually separate insulators and clamps, facilitates the handling thereof and avoids the necessity of assembling the parts 1 and 2 at the place of installation.

While I have shown and described a particular form of my invention, changes may be effected therein without departing from the spirit and scope thereof, as set forth in the appended claims.

I claim as my invention:

1. In a conductor insulating support, the combination with an insulator comprising a metal supporting hood and an insulating member disposed thereunder to be protected thereby, of a conductor clamp comprising a metal member having an elongated portion

- extending parallel to the conductor and an integral headed shank on the elongated portion for coöperative holding relation to said insulating member.
- 5 2. In a device for supporting and insulating a trolley conductor, the combination with an insulator comprising a metal supporting hood and a body of insulating material formed and related to the hood to be 10 entirely protected from above thereby, of a conductor clamp comprising a metal member extending along the conductor and having an integral portion for interlocking relation to said insulating material.
- 15 3. In a device for supporting and insulating a trolley conductor, the combination with an insulator comprising a metal supporting casing of substantially inverted cup-shape, and a body of molded insulating material disposed entirely therein, of a con-

ductor clamp comprising a metal member extending along the conductor and having an integral headed shank embedded in said insulating material.

4. In a conductor insulating support, the combination with an insulator comprising a metal supporting casing of substantially inverted cup-shape and a body of molded insulating material disposed entirely within the casing, of a conductor clamp comprising an elongated metal member extending along the top of the conductor in substantially parallel relation thereto and having an integral headed portion projecting from an intermediate position thereof into said mold- 30 ed material.

In testimony whereof, I have hereunto subscribed my name this 26th day of Aug., 1919.

NILS J. A. WAHLBERG.
